UNITED STATES PATENT OFFICE

HAROLD WARREN, OF LYNN, MASSACHUSETTS, ASSIGNOR TO UNITED SHOE MACHINERY CORPORATION, OF PATERSON, NEW JERSEY, A CORPORATION OF NEW JERSEY

SCOURING MACHINE

Application filed February 27, 1924, Serial No. 695,558. Renewed December 1, 1926.

This invention relates to scouring machines. The invention is illustrated as embodied in a machine designed for scouring heels.

5 In the manufacture of men's shoes provided with multi-section heels (for example heels with leather base sections and rubber top sections), it has been found desirable to form substantially the final surface upon the 10 breast of the heel base of such a heel prior to its attachment to the shoe in order to avoid the possibility of damage to the shoe by the knife of a heel breeding machine or of damage to the shank of the sole from the 15 attempt to scour the base of the heel into the sharp corner formed by the shoe sole and the breast of the heel base. It has been found also that the breast face at the heel base can be formed more quickly and accurately before 20 the base is attached to the shoe. In such cases it has been proposed, as set forth, in Serial No. 655,541, Letters Patent No. 1,554,312, granted September 22, 1925, on an application filed 25 August 3, 1923, by George E. Warren, that the breast surface of the top section be scoured and otherwise finished to accord with the breast surface of the already finished heel base.

With this in view, one object of the present 30 invention is to provide a machine adapted for scouring the breast surface of the top section of a multi-section heel conveniently and accurately.

In accordance with a feature of the invention, 35 the scouring element of the illustrated machine consists of an endless belt which is mounted upon a movably supported frame and driven by means, illustrated as an electric motor, also carried by said frame. The 40 frame is constructed and arranged to present a limited part of the driven belt to the work at any given instant and is movably mounted on the machine so that it constitutes a self-contained unit by means of which this operating portion of the belt may be presented to and moved along the surface of the work. Preferably the frame is so supported that the operating point of the belt is movable 45 along a predetermined path.

50 Another feature of the invention consists

in a novel arrangement for supporting a shoe with relation to the scouring element, such that even though there be irregularities or inaccuracies in the conformation of the breast surface of the heel base, the scouring 55 of the top section of the heel will be accurately gaged by the contour of the corresponding part of the heel base and the scouring means will be so applied to the top section of the heel as to finish its breast in exact correspondence with the actual breast surface of the heel base.

Still another feature of the invention resides in a novel gaging device supported adjacent to one edge of the scouring element at 60 the active operating point thereof and arranged to contact with the breast of a heel. This gaging device may advantageously be arranged both to effect a preliminary positioning of the heel and to control the position of the heel with respect to the scouring element during the operation upon the breast of the heel. As illustrated, this gage takes 65 the form of a thin plate supporting one edge of the abrasive belt and having a curvature 70 substantially like that of the breast of the heel to be scoured.

Another object of the invention is to provide an arrangement for supporting the shoe 75 such that the curved side and rear peripheral surfaces of a heel section as well as the heel breast may conveniently be scoured without the necessity of accurate guiding on the part of the operator. To this end, the shoe is mounted upon a pivoted support (which is 80 bodily movable as well), and guiding means are provided for moving the shoe on its support past the operating point of the scouring tool. For this operation, the frame carrying the scouring belt is held in fixed position 85 with respect to the base of the machine.

The machine may advantageously be utilized in this manner both in those cases in which the side and rear surfaces of heel bases 90 are trimmed before the heel bases are attached to the shoes and those cases in which the trimming has been delayed until after the application of the top sections of the heels. In either case, however, the outer surface of the top section conforms closely to the outer 95

surface of the heel base and the function of the machine is simply to perform a finishing operation to render this surface continuous and smooth rather than to make a roughing cut to remove any substantial quantity of material.

For a more complete understanding of the preferred embodiment of the invention reference is had to the accompanying drawings in which:

10 Fig. 1 is a perspective elevation of the machine arranged for scouring the breast of a rubber heel top section,

15 Fig. 2 is a plan view of the same arrangement,

Fig. 3 is a side elevation partly in section showing the relation of the tool and the breast of the heel.

20 Fig. 4 is a section showing the rand crease guide for the heel, and

Fig. 5 is a view illustrating the arrangement of the machine when it is utilized for scouring the outside surface of a heel.

25 Preferably the machine will be mounted on a bench or table 10 and comprises an upright standard 12 provided at its upper end with a bearing 14. Rotatably mounted on this bearing and supported by means of a pin 16 is a frame 18 provided with a forwardly extending arm 20, lateral arms 22 and 24, and an arm 26, extending to the rear, which constitutes a support for a motor 30 arranged with its shaft in a vertical position. This motor is secured to the arm 26 by means of 30 a clamp 28 and an adjustable stop 32 on the motor is arranged to contact with the upright 12 to limit the movement of the frame 18 in one direction. A handle 33 is secured to the upper end of the pin 16 and suitable ball 35 bearings may be provided between said handle and the bearing 14 to insure easy movement of the frame on the standard. Mounted on the lower end of the shaft of the motor is a flanged pulley 36 which, together with similar pulleys 38 and 40 mounted on the arms 24 and 22, respectively, supports an abrasive belt 42 serving as a scouring element. Thus the lower edge of the belt moves closely adjacent to the base of the heel and in a plane 40 near the plane of the sole of the shoe. A fourth pulley for the belt 42 is provided at the forward end of the arm 20 in the form of a depending stud 44 on which there is mounted a rotatable sleeve 46 (Fig. 3) provided with a shoulder between its ends and resting at its lower end upon a gage 50. This gage, as indicated in Figs. 2 and 3, has an oval shape designed preferably so that a portion of its forward edge has a curvature approximately like that of the breast of the heel base. It is positioned upon the stud so as to underlie and support the abrasive belt not only at its ends but at its central point where the belt is in operative engagement 50 with the heel. Here it projects beyond the

sleeve 46 (see Fig. 3) an amount equivalent to the thickness of the abrasive belt so as to control its action. The gage 50 is extended laterally for a sufficient distance to insure its easy contact with the corner of the leather heel base of a heel as the machine is swung from a side position, which ordinarily will be determined by the position of the stop 32, to a position where said gage 50 contacts with the corner of the heel breast. It will be noted from Fig. 3 that the bottom face of the gage is beveled to allow clearance for the shank of a shoe in order to allow full freedom of contact between the operative face of the belt and the breast of the heel. The kite shaped arrangement of the belt pulleys projects one portion of the belt to form a bulged portion constituting an operating point and allows room for the sole of the shoe between its reaches.

55 It will be noted that the bearing 52 for the pulley 40 is mounted upon a block 54 slidable in a groove in the outer end of the arm 22 and spring 56 is compressed between this block and an abutment on the arm 24 (Fig. 2) so as to push the bearing 52 outwardly to keep the belt taut. A thumb screw 60 is arranged to force the block 54 inwardly when it is desired to apply a new belt and a guard member 62 is provided to prevent the block 54 from being forced out of its groove in case of accidental breakage of the abrasive belt.

60 A support for the work comprises a vertical standard 70 rigidly attached to a block 72 provided with grooves designed to coact with the overhanging ledges 76 of a base plate 78 on the table 10. This block 72 is urged forwardly toward the abrasive belt to effect adequate contact of the tool and work by means of a spring 80 between one end of said block and an adjusting screw 82 threaded in a block 84 which is screwed to the base plate 78. The forward limit of movement of the work support is determined by an adjustable screw 86 threaded in a block 88 which is screwed to the plate 78. The path of movement of the block 72 will be seen to intersect the center of oscillation of the frame 18. Guard plates 90 and 92 may be attached to the upper edges of the ledges 76 to prevent the entrance of dust into the space between the sliding block 72 and the base plate 78. On the upper end of the standard 70 is a work rest 94, which is slidable vertically and is normally spring-pressed upwardly by a spring 96 received in a socket of said rest and bearing against the upper end of the standard 70. A pin 98 coacting with a groove 100 may be used to limit the upward movement of the work rest 94 and forms a convenient means of securing it in depressed position against the tension of the spring 96. If the machine is to be utilized for work of that type in which position holes have been provided in the heel seat of the shoe extending 105

into the heel base and the rubber heel section, then it will be convenient to provide upstanding pins 102 to engage corresponding holes in the work and firmly to position it in a predetermined location with respect to the axis of oscillation of the frame 18 carrying the abrasive belt.

10 A holddown for the work is provided in the form of a tread-engaging plate 106 pivotally mounted upon the end of a stud 108 which is supported at the upper end of an arm 110 pivotally mounted on the block 72. The arm 110 may be swung to one side out of the way of the operator when a new piece of work is being inserted in the machine. When 15 it is swung back to operative position the holddown plate 106 will engage the tread of the heel and, compressing slightly the spring 96, maintain the work at a fixed height with respect to the sliding block 72.

In the operation of the machine for scouring the breast of a rubber heel section, the swinging frame will be moved to the position determined by the stop 32 and a shoe, having been mounted upon the heel plate 94, will be swung into longitudinal relation to the plate 72 thus allowing the pin 98 to enter the vertical portion of the slot 100 and prevent further rotation of the work. The holddown 106 will then be swung into engagement with the tread of the heel slightly to compress the spring 96 and hold the work tightly in place. Assuming that the motor is in operation, the swinging frame will then be moved in a plane substantially parallel to the tread face of the heel or to the plane of the edge of the belt by means of handle 33 to bring the operative point on the swiftly moving abrasive belt 42 into engagement with the work. As the gage 50 approaches the corner of the heel, its curved end surface will meet the corner of the breast of the leather heel base to effect a preliminary positioning of the heel and gradually guide the operative bulged portion of the belt where it surrounds the rotatable sleeve 46 into engagement with the breast of the heel and at the same time the gage will limit the relative movement of approach between the tool and the work thereby locating or determining the position of the latter. The point of contact of the abrasive belt 42 with the work will be along a substantially vertical line which will be approximately parallel to and in front of the axis of the stud 44 mounted on the end of the arm 20 of the swinging frame and this line will shift as the frame is moved to transfer the point of operation along the work. Preferably, and as illustrated in Fig. 2, the machine will be designed so that the arc of the active portion of the forward edge of the gage 50 and the arc described by the movement of the operating portion of the abrasive belt will be substantially the same as the arc of the breast of the heel upon which the work is to be done.

It has been found, however, that the actual curvature of various heels does not exactly conform to the predetermined path of movement of the operative part of the belt and for this reason the support 70 is mounted upon the sliding block 72 so that under the action of the gage member 50, the work and the support may, if necessary, be forced back slightly against the tension of the spring 80. The result will be that the breast of the top section, here shown as a rubber heel, will be scoured to correspond exactly with the breast of the leather heel base.

In order to utilize the machine for scouring the curved side and rear peripheral surfaces of the heel, the arrangement illustrated more completely in Fig. 5 will be utilized to support the shoe, and it will be noted that the arrangement of the operating tool only differs from that employed for scouring the breast of the heel in that the gage 50 has been removed and a rand crease guide in the form of a thin rotatable disk 130 (Fig. 4) has been substituted. Like the gage 50, this rand crease guide will assist in supporting the abrasive belt on the spool 46 and is itself held on the stud 44 by a screw 132. When the machine is used for this operation, the frame 18 carrying the abrasive belt is maintained in a fixed position by means of a set screw 134 passing through the bearing 14 to engage the pin 16. The work support (Fig. 5) is mounted upon an arm 140 which is pivotally secured to the table 10 by means of a stud 142, and the arm is urged toward the operating tool by a spring 144 secured to a post 146 in the table, the tension of this spring being adjustable by means of a thumb nut 148. A vertical post 150 in the outer end of the arm 140 carries a sleeve 152 which is provided with a curved slot 154 coacting with a pin in the post 150. On the upper end of the sleeve 152 is a work-engaging support 160 having a sliding connection 162 with the upper end of the sleeve, and preferably provided with pins 164 corresponding to the pins 102 of the form previously described. A post 170 provided with a spring-pressed locking pin 172 may be mounted at the position indicated by the hole 174 (Fig. 1) in the plate 92 to lock the arm 140 temporarily in a convenient position for mounting the work upon the work support.

In the particular type of work for which the illustrated arrangement was designed, the surface of the breast of the heel may be generated by means of a right line located at an angle of 86 degrees with respect to the plane of the tread of the heel, and the outer surface of the heel is generated by a right line moving parallel to the line which generated the breast of the heel. The operative part of the abrasive belt is substantially vertical. The shoe must be tilted, therefore, to bring the curved periphery of the heel into full contact as the shoe is turned on the support. It is for this 120
125
130

reason that the slot 154 is curved in its particular fashion so as to maintain the level of the rand crease substantially at the level of the rand crease guide 130. By swinging the 5 arm 140 and by sliding the work support 160 upon the sleeve 152, the outer surface of the heel will be maintained in contact with the abrasive belt and the outer surface of the rubber heel top section and the outer surface 15 of the leather heel base scoured.

Having thus described the invention, what I claim as new and desire to secure by Letters Patent of the United States is:—

1. In a machine for scouring heels, a scouring tool, means for supporting the heel of a shoe for presentation to said scouring tool constructed and arranged to allow movement toward and away from the tool, resilient means urging the heel toward the tool, a gage 15 adjacent to the tool adapted to engage a portion of the shoe to limit the movement of the heel toward the tool, and means for effecting a relative movement of the heel and the scouring tool to present various portions of 20 the heel to the tool.

2. In a machine for scouring heels, a pivoted supporting frame, a driving motor mounted on said frame, an abrasive belt supported by the frame to be driven by the motor, means 25 for supporting a shoe for presenting the top section of the breast of a heel to said abrasive belt constructed and arranged for movement in a fixed path toward and away from the path of oscillation of said supporting frame, guiding means on the pivoted frame arranged to engage the breast surface of the heel base, and means for urging the work toward the abrasive belt.

3. In a machine of the class described, 30 means for supporting a heel to present the breast of the heel to an abrasive tool, said tool comprising an endless abrasive belt mounted upon a movable supporting frame, means for projecting a portion of said belt, a gage member associated with the belt adjacent to its 35 projected portion, and means permitting longitudinal movement of the work support toward and away from the tool under the guidance of said gage.

4. In a machine for scouring heels, movable means for supporting a heel to present the breast of the heel, resilient means urging said movable means in one direction, an abrasive tool, means for supporting said tool for movement along a predetermined path, and a guiding gage adapted to engage a portion of the 45 breast of the heel thereby to move said work support against the tension of the resilient means to cause the tool to traverse the actual curve of the breast of the heel.

5. In a machine employing an endless abrasive belt, a movably mounted supporting frame provided with a plurality of devices for movably supporting said belt constructed and arranged to project one portion there-

of to form a corner for contact with the work, and an electric motor mounted on said frame constructed and arranged to drive the belt on its supporting frame whereby the mechanism is self-contained and the frame, belt and motor may be moved to present the projected corner of the belt to various portions of the work. 70

6. In a machine of the class described, a supporting standard, a frame pivotally mounted on said standard and provided with a plurality of arms, flanged pulleys mounted on some of said arms, an electric motor on the frame operatively connected to one of said pulleys, another of said arms being provided with a pulley and a rigidly-supported gage member adjacent to one end thereof in place of one of its flanges, and an abrasive belt surrounding said pulleys. 75

7. In a machine for scouring heel breasts, a pivotally mounted supporting frame, an endless abrasive belt, an electric motor mounted upon said frame arranged to drive said belt, guiding means on said frame for supporting and guiding said belt about an open path designed to receive and avoid the sole of a shoe and for projecting the belt to provide an operating point, and means for supporting a shoe with the sole thereof within the reaches of said belt and with the heel breast surface thereof in position for engagement with the operating point of said abrasive belt as the frame is moved to transfer the point of operation along the work. 80

8. In a machine for scouring heels, a pivoted supporting frame, a driving motor mounted upon said pivoted frame, an endless abrasive belt movably supported by said frame and arranged to be driven by said motor, means for supporting the work for presentation to the abrasive belt, and means for causing movement of the supporting frame around its pivot to transfer an operating point of the rapidly driven abrasive belt across the desired surface of the work. 100

9. In a machine of the class described, means for supporting a heel in a substantially fixed position, a supporting frame provided with means for guiding an endless abrasive belt, said frame being constructed and arranged to cause one portion of the belt to project in a manner suitable for engagement with the work, means for causing the rotation of the belt around its supporting frame, and means for moving said frame to cause the work-engaging projected portion of the belt to traverse the periphery of the heel along a fixed path. 110

10. In a machine for scouring heels, an operating tool, a slidably work support arranged to cause the work to approach or recede from the operating tool, a supporting jack on said slide, and means including a member engaging the tread face of the heel constructed and arranged to maintain the 115

same at a fixed level so that the work will be properly presented to the face of the operating tool.

11. In a machine for securing the outer surface of the heel of a shoe, a rotary abrasive tool, a rand crease guiding device mounted adjacent to one periphery of the tool, a movable support for the shoe, resilient means urging said support toward the tool, means allowing oscillation of the shoe upon the support, and a guiding means constructed and arranged to raise and lower the work upon its support as it is oscillated to bring various sections of the surface of the heel into operative relation with the tool so that the rand crease of the work shall be maintained substantially at the level of the rand crease guide on the tool.

12. In a machine for scouring heels, a scouring tool, means for supporting a shoe heel for presentation to said scouring tool, means for causing relative movement of the scouring tool and the heel support to effect adequate contact of the tool with the work during the scouring operation, a gage adjacent to the tool adapted to contact with a portion of the heel to limit such relative movement, and means for effecting relative movement of the heel and the scouring tool in a plane substantially parallel to the plane of the tread face of the heel to cause the tool to act upon various portions of the heel.

13. In a scouring machine, an endless abrasive belt, means for supporting said belt arranged to drive the belt, means for projecting a portion of said belt to form a bulge for contact with a piece of work, and means for shifting the position of said bulged portion in a plane substantially parallel to the plane of the edge of the belt.

14. In a scouring machine, an endless abrasive belt, means for supporting said belt arranged to drive the belt, means for projecting a portion of said belt to form a bulge for contact with a piece of work, and means for effecting relative movement of the work and the bulged portion in a plane substantially parallel to the plane of the edge of the belt to transfer the point of operation along the work.

15. In a machine for scouring the breasts of the heels of boots and shoes, a scouring device, and a gage member mounted adjacent to the periphery of the scouring device, said gage member having a portion of its outline shaped to correspond substantially to the curvature of the breasts of the heels to be scoured, whereby the position of a heel being presented to said scouring device may be determined by contact with said gage member.

16. In a machine for scouring the breasts of the heels of boots and shoes, an abrasive scouring belt, supporting means therefor adapted to present a portion of said belt to scour the breasts of heels, and a gage plate

arranged adjacent to the edge of said scouring belt a portion of the outline of which gage plate corresponds to the curvature of the breasts of the heels to be scoured, whereby said heels may be located with respect to the scouring belt by contact with said gage member.

17. In a machine for scouring the breasts of the heels of boots and shoes, an endless abrasive belt, means for supporting said belt, and means for retaining said belt upon said supporting means including a gage member projecting beyond said belt adjacent to one edge thereof, said gage member being constructed and arranged for contact with the breast of a heel during the presentation of said heel breast to said abrasive belt.

18. In a machine for scouring the breasts of rubber toplifts upon the heels of boots and shoes, an abrasive scouring belt, means for supporting said belt, and means for retaining said belt upon said supporting means comprising a gage plate positioned adjacent to one edge of the abrasive belt and constructed and arranged to determine the position of the rubber toplift with respect to the abrasive belt by contact with the breast of the heel base.

19. In a machine for scouring rubber toplifts attached to the bases of boots and shoes, an endless abrasive scouring belt, means for supporting said belt for movement in a substantially horizontal plane, and means for retaining said belt on said supporting means including a gage projecting beneath the lower edge of the belt, said gage having a portion of its outline curved to agree with the curvature of the breast of the base of a heel so that the approach of the rubber toplift to the scouring device is controlled by the engagement of said gage with the breast of the heel base.

20. In a machine for scouring the breasts of the heels of boots and shoes, an endless abrasive belt, means for supporting said belt and projecting a portion of the belt to form a bulge for contact with the heel, and means for retaining said belt on said supporting means including a gage plate arranged beside the edge of the belt adjacent to the bulged portion thereof, said gage plate having a portion projecting a substantial distance beyond the abrasive belt for use in effecting a preliminary positioning of the heel.

21. In a machine for scouring heels, means for supporting and driving an endless abrasive scouring belt arranged to provide an open space within the run of the belt for the reception of the sole of a shoe being presented to the belt and to project a portion of the belt to form a bulge for contact with the heel, and heel-gaging means positioned adjacent to said bulged portion of the scouring belt adapted to contact with a portion of the breast of the heel.

22. In a machine for scouring heels, means for supporting and driving an endless abrasive belt arranged to provide an open space within the run of the belt for the reception of the sole of a shoe being presented to the belt and to project a portion of the belt to form a bulge for contact with the heel, and heel-gaging means positioned adjacent to said bulged portion of the scouring belt adapted to contact with a portion of the breast of the heel, said gaging means contacting with the edge of said abrasive belt to support and guide it. 70
23. In a machine for scouring heels, means for supporting and driving an endless abrasive belt arranged to provide an open space within the run of the belt for the reception of the sole of a shoe being presented to the belt and to project a portion of the belt to form a bulge for contact with the heel, heel-gaging means positioned adjacent to said bulged portion of the scouring belt adapted to contact with a portion of the breast of the heel, and means for effecting relative movement of the heel and the bulged portion in a plane substantially parallel to the plane of the edge of the belt to transfer the point of operation along the work under the guidance of said gaging means. 75
24. In a machine for scouring heels, an endless belt mounted upon a movable supporting frame, means for projecting a portion of said belt to form a bulge for contact with the heel, and a gage member associated with the belt adjacent to its projected portion, a portion of the contour of said gage member being like the desired contour of the breast of the heel and adapted to contact with the heel breast as the heel is presented to the belt. 80
25. In a machine for scouring heels, an endless belt mounted upon a movable supporting frame, means for projecting a portion of said belt to form a bulge for contact with the heel, a gage member associated with the belt adjacent to its projected portion, a portion of the contour of said gage member being like the desired contour of the breast of the heel and adapted to contact with the breast surface of the heel base as the heel is presented to the belt, and means for effecting relative movement of the heel and the bulged portion of the belt to transfer the point of operation along the breast of the heel. 85
26. In a machine for scouring the breasts of the heels of boots and shoes, a driven scouring device having an edge portion adapted to be moved in a path other than the path in which it is driven in a plane closely adjacent to the plane of the sole of the shoe to which the heel has been attached, and a gage member supported adjacent to said edge at the active operating point thereof constructed and arranged to contact with the breast of a heel thereby to determine the action of the scouring device upon the heel. 90
27. In a machine for scouring the breasts of the heels of boots and shoes, a movable scouring element having an active operating portion adapted to be brought into contact with the breast of a heel so that one edge of the scouring element is closely adjacent to the base of the heel, and a gaging device supported adjacent to said edge of the scouring element arranged to contact with the breast of the heel to assist the operator in positioning the heel with respect to the scouring element. 95
28. In a machine for scouring the breasts of the heels of boots and shoes, a scouring element having an active operating portion adapted to be brought into engagement with the heel breast, and a gaging device supported adjacent to one edge of the scouring element at the active operating point thereof constructed and arranged both to effect a preliminary positioning of the heel and to control the position of the heel with respect to the scouring element during the operation upon the breast of the heel. 100
29. In a machine for scouring the breasts of the heels of boots and shoes, a driven scouring device having an active operating portion, and a gage member associated with the scouring device adjacent to its active portion, a portion of the contour of said gage member being like the desired contour of the breast of the heel and adapted to contact with the heel breast as the heel is presented to the said scouring device. 105
